UNITED STATES PATENT OFFICE.

ISAAC BROOKE, OF POTTSTOWN, PENNSYLVANIA.

DESIGN FOR A MONEY-BOX.

SPECIFICATION forming part of Design No. 15,983, dated March 24, 1885.

Application filed January 5, 1885. Term of patent 3½ years.

To all whom it may concern:

Be it known that I, ISAAC BROOKE, a citizen of the United States, residing at Pottstown, in the county of Montgomery, State of Pennsylvania, have invented and produced a new and original Design for a Toy Money-Box, of which the following is a specification, reference being had to the accompanying photographic illustration, forming part thereof.

10 The leading feature of my design for a money-box is the box of the form of a stove, and the ornamentation of the same.

15 A represents a money-box of the form of a stove, consisting of the base or ash-pit *a*, cylinder *b*, combustion-chamber *c*, rings *d* *e*, cap *f*, and top ornament, *g*. The ring *d* is intermediate of the two sections of the cylinder *b*, and the ring *e* is between the cylinder *b* and combustion-chamber *c*. In the chamber *c* is a 20 money-inlet, *h*. The ash-pit *a* has on its sides scallops *k*, with which alternate the points *m*. At the bottom of the cylinder *b* is a band, *n*, which is of greater diameter than said cylinder. The upper part of the cylinder has 25 imitation doors *p*, and the chamber *c* is pan-

eled, as at *q*. The cap *f* has a circular row of dots, *r*, and the ornament *g* is of shield shape, the central point at top being surmounted by scrolls *s*. On the face of the ornament are scrolls *t*.

30

I claim--

1. A design for a toy money-box of the form of a stove, having the ash-pit *a*, two-part cylinder *b*, having a band, *n*, of greater diameter than the base of the cylinder, combustion-chamber *c*, having vertically-elongated opening *h*, rings *d* and *e*, cap *f*, and top ornament, *g*, as shown and described. 35

2. A design for a toy money-box of the form of a stove, consisting of the ash-pit *a*, two-part cylinder *b*, combustion-chamber *c*, having vertically-elongated opening *h*, rings *d* and *e*, cap *f*, and top ornament, *g*, said ash-pit having scallops *k* and points *m*, and said ornament *g* being of the form of a shield with scrolls *s* *t*, 40 as shown and described. 45

ISAAC BROOKE.
